[57] CLAIM

The ornamental design for a plaque with an ancestral tree, as shown and described.

DESCRIPTION

FIG. 1 is a front elevational view of a plaque with an ancestral tree showing my new design;

FIG. 2 is a top plan view thereof on a reduced scale, the bottom plan view being a mirror image;

FIG. 3 is a right side elevational view thereof, the left side elevational view being a mirror image; and

FIG. 4 is a rear elevational view thereof.
